UNITED STATES PATENT OFFICE.

JOHN MODINI, OF WASHINGTON, DISTRICT OF COLUMBIA.

EXHIBITING DEVICE.

SPECIFICATION forming part of Letters Patent No. 356,005, dated January 11, 1887.

Application filed October 11, 1886. Serial No. 215,921. (No model.)

To all whom it may concern:
Be it known that I, JOHN MODINI, of Washington, in the District of Columbia, have invented certain new and useful Improvements 5 in Exhibiting Devices; and I do hereby declare that the following is a full, clear, and exact description thereof, reference being had to the accompanying drawings, and to the letters of reference marked thereon, which form part of 10 this specification, in which—

Figure 1 is a front view of a frame and stand embodying my invention. Fig. 2 is a central vertical section on line $\alpha\alpha$, Fig. 1. Fig. 3 is a plan view of the frame detached with the 15 part E raised. Figs. 4 and 5 are details.

This invention relates to improvements in picture-frames and supports or exhibiting devices, and has special reference to the construction of frame and the means for suitably 20 holding therein one or more photographs, engravings, or paintings, as will be fully understood from the following description, and particularly specified in the claims.

In the drawings, A designates the frame 25 proper, and G the supporting-stand, composed of base-piece H and easel J, as hereinafter described.

The frame A is composed of a back, B, which may be of any desired shape, either round, 30 oval, or, as shown in the drawings, square. Around the outer edges of the back is a reinforcing strip, a, which may, if desired, be formed integral with the back by making the latter of a suitable molding. This strip or 35 bead a is intended to be ornamented in any desired manner, the ornamentation extending inward from the bead a a suitable distance on the face of back B, to present a finished appearance when the hinged outer part, E, of 40 the frame, hereinafter described, is closed. The desired finish is effected in the present instance by the use of plush, with which the bead and the adjoining parts of the back B are covered, the plush being glued thereto, and 45 having a number of ornamental tacks or screws upon the outer face of the bead a, as shown in Fig. 1. At the top of back B, beneath the plush or other ornamentation, is a small lock, b, for a purpose hereinafter explained.

50 C C' designate cords or wires, which are respectively on the right and left and top and bottom sides of back B, being secured thereto,

just at the inner edge of the ornamented border, by means of suitable screws or tacks at each corner of the back, as shown. Upon the 55 cords C are secured bands of ribbon or other suitable material, D, which have their ends looped around the cords, as shown, so that the bands can be adjusted upon the cords C in relation to each other and to corresponding 60 bands, D', which are secured upon the cords C'. c c' designate bands, of material similar to bands D D', which are secured at right angles to each other centrally between the edges of back B, as shown, but are not adjustable. If 65 desired, these bands c c' may be omitted when the frame is to contain only large pictures.

E designates the hinged outer part of the frame, which is composed of the frames F F', 70 F'', corresponding in shape to the back B. The frame F lies next to back B when the part E is closed, and is made of less diameter than the back, so that when closed its outer edge will lie within the bead a thereof. This frame may be also ornamented, and is provided with 75 the glass f. Frame F' is made sufficiently small to fit snugly within frame F above the glass f, (so that the outer faces of the frames F F' are flush,) and is also ornamented in a suitable manner.

The outer frame, F'', of part E is made of 80 narrow stuff, suitably ornamented, and of such size that when placed above and secured to frames F F' it will not cover the outer edge of the former nor the inner edge of the latter, as 85 shown. These three frames, when thus secured together, form, with the back B, a very strong, compact, and handsome setting for the pictures therein.

The part E is hinged at one side to the back 90 B, opposite the lock b, by means of suitable hinges, e, which are secured to the back B and frame F, respectively, and are designed to be hid from sight by the ornamentations of the frame when the part E is closed. If desired, 95 the part E may be provided with a knob, f', by which the opening and closing of the frame is more quickly effected.

G designates the frame-support, having the base portion H, which may be of any desired 100 contour, having preferably a straight outer edge and rounded at its rear portion. This base is provided with three notches or recesses, h, two at its front corners and one at

rear, the notches forming a triangle and serving a purpose hereinafter explained. The support proper is an easel, J, having the usual uprights and cross-pieces and hinged rear leg, 5 and the lower cross-bar is provided with two or more knobs, j, which serve to keep the frame A in position. The upper cross-piece of the easel is provided centrally with ring j', which is engaged by a hook on the back of frame A 10 to keep the latter from tipping forward and off the easel.

The lower ends of the legs of the easel J are inserted in the recesses h of base H, as shown, and being retained therein the easel is held 15 firmly in position when the frame A is placed thereon.

The frame A may be provided with cord and attaching devices, as shown, by which it may be suspended from a wall, if desired.

20 I propose covering the entire device, frame, and support with plush, and by using different shades of the same for different parts very fine effects can be obtained. The base H of the support I also propose providing 25 with raised plush flowers and designs, the same being secured thereto by a number of small bright-head tacks along the edges, so that the design will stand out in bold relief. The rear end of the base H may be raised, the 30 rear perforation, h, permitting the rear leg of the easel to slide through it. By so doing the figures on the base are brought into more prominence.

By the use of the adjusting-bands D D' upon 35 cords C C' the interior of the frame can be divided into two or more equal or unequal compartments for the reception of small engravings or photographs, as is evident, so that each photograph will be divided from the 40 next, and by their means the device is well adapted for exhibiting valuable laces and other articles in fancy stores.

Having described my invention, what I claim is—

45 1. A picture-frame having a suitable back

and a hinged front and sets of cords C C', secured to the back and carrying bands D D', of suitable material, whereby the interior of the frame may be divided into two or more spaces for the reception of articles, all substantially as and for the purpose specified. 50

2. The combination, with the back B, having the cords C C', carrying the adjusting-bands D D', of the part E, composed of frames F F' F'', having glass f and hinged to back B, 55 and a suitable retaining device to keep the same locked, all constructed and arranged substantially in the manner and for the purpose specified.

3. The combination, in a frame, of the back 60 B, having bead a, cords C C', carrying adjusting-bands D D' and fixed bands c c', as described, and lock b, with the part E, composed of inner frame, F, carrying glass f, frame F', secured within frame F over the glass, and 65 frame F'', secured centrally over frames F F', hinges e e, and staple e', all constructed and operated substantially as and for the purpose described.

4. An exhibiting device for pictures, &c., 70 composed of frame A and support G, the frame A being composed of back B, having cords C C' and adjusting-bands D D', operated as described, and part E, composed of frames F F' F'', hinged to back B and adapted to be 75 locked thereon, as described, the part G being composed of base H, having openings or recesses h, and easel J, having knobs j, and having its feet held in the recesses h of the base H, the frame and support being highly 80 ornamented, all substantially as and for the purpose specified.

In testimony that I claim the foregoing as my own I affix my signature in presence of two witnesses.

JOHN MODINI.
